UNITED STATES PATENT OFFICE

92,678

DESIGN FOR A COMBINED LAMP BASE AND SHADE

Ludwig Rath, New York, N. Y., assignor to The
Mantle Lamp Company of America, Chicago,
Ill., a corporation of Illinois

Application February 19, 1934, Serial No. 50,770

Term of patent 3½ years

To all whom it may concern:

Be it known that I, LUDWIG RATH, a citizen of the Republic of Austria, residing at 375 Riverside Drive, Apartment 11-B, New York city, in the county of New York and State of New York, has invented a new, original, and ornamental Design for a Combined Lamp Base and Shade, of which the following is a specification, reference being had to the accompanying drawing, forming a part thereof.

The figure is a view in elevation of a combined lamp base and shade, showing my new design.

The design, which is the same when viewed

from any side thereof, comprehends a frustoconical shade surmounting and having its lower end disposed proximate a substantially spherical base which terminates in an outwardly-flared lower end. The contour of the entire device, as delineated by its straight and curved lines, is such as to give it a new, pleasing and odd appearance.

I claim:

The ornamental design for a combined lamp base and shade, substantially as shown and described.

In testimony whereof I affix my signature.
LUDWIG RATH.
